(57) **CLAIM**

What is claimed is the ornamental design for an artificial jewel for skin body art, as shown and described.

DESCRIPTION

FIG. 1 illustrates a top perspective view of an artificial jewel for skin body art, according to a first embodiment;

FIG. 2 illustrates a front view thereof;

FIG. 3 illustrates a rear view thereof;

FIG. 4 illustrates a right-side view thereof;

FIG. 5 illustrates a left-side view thereof;

FIG. 6 illustrates a top view thereof;

FIG. 7 illustrates a bottom view thereof;

FIG. 8 illustrates a bottom perspective view thereof;

FIG. 9 illustrate another and different bottom perspective view thereof;

FIG. 10 illustrates a top perspective view of an artificial jewel for skin body art, according to a second embodiment;

FIG. 11 illustrates a front view of the second embodiment;

FIG. 12 illustrates a rear view of the second embodiment;

FIG. 13 illustrates a right-side view of the second embodiment;

FIG. 14 illustrates a left-side view of the second embodiment;

FIG. 15 illustrates a top view of the second embodiment;

FIG. 16 illustrates a bottom view of the second embodiment;

FIG. 17 illustrates a bottom perspective view of the second embodiment; and,

FIG. 18 illustrate another and different bottom perspective view of the second embodiment.

The broken lines in the figures depict portions of the artificial jewel for skin body art that form no part of the claimed design.
